UNITED STATES PATENT OFFICE.

CARLTON A. JOHNSTON, OF NEW ROCKFORD, NORTH DAKOTA.

PIPE GRIP.

Application filed September 14, 1921. Serial No. 501,545.

To all whom it may concern:

Be it known that I, CARLTON A. JOHNSTON, a citizen of the United States, residing at New Rockford, in the county of Eddy and State of North Dakota, have invented certain new and useful Improvements in Pipe Grips, of which the following is a specification, reference being had to the accompanying drawings.

10 This invention relates to devices for use in drilling wells, and particularly to a pipe gripping member adapted to be used for supporting strings of pipe in well drilling operations, as for instance when a new section of pipe is to be screwed into a lower section of pipe.

15 The general object of the invention is to provide a very simple, strong and effective pipe grip which may be readily gripped around a pipe, and which, when gripped around a pipe, will fit the same firmly and prevent any downward movement of the pipe.

20 A further object is to provide a device of this character formed in two sections detachably engaged with each other so that the sections, which constitute jaws, may be opened for placing around the pipe and then closed to secure gripping engagement with the pipe, the pipe grip being of such character that when it is tilted it will bind upon the pipe and when it is disposed in a plane at right angles to the pipe it will not bind thereon but may be slipped up and down on the pipe.

25 My invention is illustrated in the accompanying drawings, wherein:—

30 Figure 1 is a top plan view of a pipe gripping member constructed in accordance with my invention;

35 Figure 2 is a side elevation of the construction shown in Figure 1;

40 Figure 3 is a top plan view of a modified form of the pipe gripping member;

45 Figure 4 is a detail sectional view of the blade 26.

50 Referring to these drawings, it will be seen that the pipe grip comprises a body portion formed of two jaw members 10 and 10^a, these members being detachably engaged or pivoted to each other, as will be later described, and when together being

circular in plan to define a central aperture 11. The body 10 is formed with two oppositely disposed, protuberant portions 12 and 13 constituting ears, and a protuberant portion which is perforated, as at 15. The section 10^a is formed with an ear 16 apertured for the reception of the shackle hook 17. The ears 12 and 13 are disposed below the outer face of the section 10, thus providing shoulders 18, and detachably engaged with the ear 12, as by the pin 25, is the section 10^a, the pin 25 constituting, when desired, a pivot upon which the two sections or jaws 10 and 10^a may swing to open or closed position. This section is formed with a semi-circular recess 22 on one face. The opposite end of this jaw section 10^a is perforated for the passage of a screw or pin 20. Mounted upon the outer face of this section 10^a is the semi-circular blade 26, the inner edge of which is beveled to form a knife edge 27, this blade being held in place by screws 28. The opposite face of the section 10 is also provided with a semi-circular blade 29 held in place by screws or other suitable means, the inner edge of this blade being also beveled.

55 It will be seen from Figure 1 that these blades are set so that the inner margins or edges project beyond the opening 22 so that the distance between the cutting edges of these blades 26 and 29 is less than the diameter of the opening 22. The shackle 17 affords a convenient means of supporting this pipe grip when out of use or when lowering pipe into a well, and the aperture 15 permits of a hook, cable or other handling device being applied to the opposite side of the pipe grip when lowering pipe into a well.

60 In use, the jaw 10^a is opened, a pipe inserted through the opening 22, and after the pipe grip has been shifted upon the pipe to any extent desired, the jaw 10^a is closed and fastened by means of the pin 20. It is to be understood that the pin 25 is also detachable so that the two sections or jaws 10 and 10^a may be entirely disengaged from each other for placing in position around the pipe and afterwards engaged by means of the pins 20 and 25, or that either pin 20 or 25 may be removed and the other pin used as the pivot upon which the jaw mem-

bers or sections may swing. The pipe is smaller than the distance between the edges 27 of the blades 26 and 29, but when the pipe gripping device is supported by the shackle 17 it turns with relation to the axis of the pipe and as a consequence these two cutting blades bind upon the pipe so that the pipe may be raised, lowered or supported in any desired position.

10 In Figure 3, I show a slight modification of the construction illustrated in Figure 1, wherein there is an annular body 30, to the opposite faces of which are attached the blades 31 and 32, these blades being such as 15 have been heretofore described, the blades being fastened in place by the screws 33. This body 30 is provided with the oppositely disposed ears 34 and 35, to one of which ears the shackle 36 is connected. This construction operates in the same manner as the construction illustrated in Figure 1, except that 20 it does not open.

In both the constructions illustrated in Figure 1 and that illustrated in Figure 3 I 25 have provided a body having a circular aperture and having semi-circular blades attached on opposite faces of the body and confronting each other. In one case, however, the body is formed in two sections. In 30 the other case, the body is formed in one section.

One of the advantages of the construction shown in Figure 1, is that it is designed to open and lock around a pipe with a pin 35 such as shown at 20, so that it can be taken off at any time without being slipped over the end of the pipe. For instance the jaws may be opened to embrace that portion of the pipe projecting out of the well and then 40 the jaws may be closed and the pin 20 may be inserted. The pipe grip may then be lowered into the well to any desired point, a flexible connection being attached to the ear 14 and to the shackle 17 so that the pipe 45 grip may be supported in a plane at right angles to the axis of the pipe. After the pipe grip has been lowered to a suitable degree, a cable may be connected to the shackle 17 by means of a block and tackle, for the purpose of lifting the pipe out of 50 the well. It will be noted that the blades 26 and 29 are disposed on opposite faces of the body of the grip, so that when the cable is tightened, the grip will tilt, and 55 inasmuch as the blades are on opposite sides of the body, their biting edges will securely bite into the pipe, making it impossible for the grip to slip, then the pipe may be raised. When the cable is loosened, the grip will 60 slide down upon the pipe, in order that the grip may take another hold, the cable may then be again tightened, and the pipe further lifted from the well. Both pins 20 and 65 25 are for the purpose of holding the jaws 25 detachably engaged with each other. In

case a pipe is lost in the well, a cable may be connected to the shackle 17, and a wire fastened in the opening 15 of the lug 14, and with the two jaws in the positions shown in Figure 1, the grip may be lowered into the well, and manipulated until the end of the pipe passes between the jaws, then the wire (not shown) which connects to the lug 14, may be slackened and the cable (not shown) tightened, in which case the grip will bite 70 into the pipe, whereby it may be raised from the well. In other words the lug 14 is for the purpose of lowering the grip into a small curb well for catching a lost pipe. Also the grip may be used for lowering and 75 lifting pipes in a well.

I claim:—

1. A pipe grip of the character described comprising a body having opposite portions defining a central, circular aperture, a 85 semi-circular blade having a cutting edge disposed upon one face of the body, the cutting edge projecting slightly beyond the aperture, a semi-circular blade applied to the opposite face of the body and projecting 90 slightly beyond the aperture on the opposite side from the first named blade.

2. A pipe grip of the character described comprising two semi-circular jaws, said jaws defining a central aperture, a semi-circular 95 blade attached to one face of one of the jaws and having its inner edge beveled and projecting beyond the wall of the aperture, a semi-circular blade carried by the other 100 jaw and disposed on the face of the jaw opposite to the face of the first named jaw having the blade thereon, said second named blade projecting inward beyond the circular aperture, and means for holding the jaws in 105 operative position.

3. A pipe grip of the character described comprising a body having two semi-circular jaws together defining a circular opening, a semi-circular blade attached to one face of one of the jaws and projecting beyond the 110 opening, a semi-circular blade attached to the opposite face of the other jaw and projecting beyond the opening, the opposite ends of the jaws having aligning perforations, and pins insertible through said 115 perforations to hold the jaws in locked engagement with each other, one of the jaws being adapted for engagement with a flexible connection.

4. A pipe grip of the character described 120 comprising a body formed of two opposed, semi-circular jaws together defining a circular opening, a semi-circular blade attached to one face of one of the jaws and projecting beyond the opening, a semi-circular 125 blade attached to the opposite face of the other jaw and projecting beyond the opening, a pin pivotally connecting like ends of the jaws to each other, and a pin detachably engaging the other ends of both jaws 130

from the first named pin and holding the jaws in locked engagement with each other, each of said jaws having a laterally projecting, perforated lug.

5. A pipe grip of the character described comprising a body formed with a central aperture, semi-circular blades disposed upon

opposite faces of the body and confronting each other and projecting slightly beyond the aperture, and a shackle attached to the 10 body.

In testimony whereof I hereunto affix my signature.

CARLTON A. JOHNSTON.
